UNITED STATES PATENT OFFICE.

GEORGE L. SCHIDING, OF YORK, PENNSYLVANIA.

SEPTIC TANK.

Application filed January 30, 1926. Serial No. 84,972.

- This invention relates to sewage purification or distributing devices, particularly to septic tanks, and has for its object the provision of a novel septic tank adapted to 5 be constructed entirely of concrete and consequently formed as complete unit adapted to be embedded within the ground at the desired location without it being necessary to add any other parts thereto.
- 10 An important object is the provision of a septic tank arrangement preferably embodying two tanks in series, both possessing many features in common, and the two not only operating to destroy the solid matter in the 15 sewage but acting also to carry off any gases which may form during decomposition, the endmost one of the series being of course provided with a seepage outlet buried within the ground for carrying off the matter.
- 20 Another object of the invention is to provide a septic tank provided internally with means operating to prevent undue agitation of the contents in case of a rapid flow of waste matter into the tank.
- 25 An additional object is the provision of a device of this character which will be simple and inexpensive in manufacture, easy to install, positive in action, efficient and durable in service, and a general improvement 30 in the art.

With the above and other objects and advantages in view, the invention consists in the details of construction, and the arrangement and combination of parts to be herein- 35 after more fully described, and claimed, and illustrated in the accompanying drawings, in which:—

Figure 1 is a vertical section taken through a pair of septic tanks arranged in 40 tandem, one receiving from the other,

Figure 2 is a plan view of one of the tanks with the cover removed, and

Figure 3 is a vertical cross section taken on the line 3—3 of Figure 1.

45 Referring to the drawing in detail, the numerals 10 and 11 designate, broadly, the two septic tanks which are arranged in series or tandem. These two tanks are, in most respects, similar but they do possess certain 50 features of difference as will be brought out hereinafter. It should, however, be stated that both tanks are preferably constructed of concrete and while it is true that they may be of any desired size and shape, it is 55 preferable that they be cylindrical and of such size as to be capable of being trans-

ported from the place of manufacture to wherever their use is needed. This feature is of importance inasmuch as there are certain tanks in existence which are incomplete owing to the fact that they must be equipped with a bottom subsequent to their mounting within the ground. The tank 10 comprises a body 12 formed at opposite sides of its interior with projections 13 and 14 with- 60 in the former of which is embedded a downwardly extending elbow 15 with which connects the waste pipe 16 leading from the plumbing system in a house or other building. 65

Within the enlargement 14 is embedded a 70 T 17 which has its two opposite branches extending vertically and which has its remaining branch 18 extending horizontally to or through the side wall of the body 12 for connection with an outlet pipe 19 which leads to 75 the tank 11, as will be described. The tank 10 is equipped with a removable cover 20 equipped with a lifting ring 21 whereby it may be removed when access is needed to the tank 10. Attention is directed to the 80 fact that the projection 14 and also the pipe 17 terminate at a point below the lower surface of the cover 20 so as to provide a space 22 through which any gases rising from the 85 decomposing matter within the tank body 12 may pass so as to enter the T 17 and pass 90 out through the pipe 19. Obviously the tank body 12 may contain any suitable liquid containing disinfectant or chemicals calculated to destroy the waste matter entering the 95 tank. This feature is common to both tanks and under some systems it is of course true that the second tank may contain a different liquid or chemical from what is contained in the first in order to exert a still further purifying action.

The tank 11 comprises a body 23 substantially the same as the body 12 and formed with enlargements 24 and 25 the latter of which contains a T 26 embedded therein in 100 identically the same manner as the T 17. However, the enlargement 24 has embedded therein a T 27 in contradistinction to the elbow 15 embedded within the enlargement 13 of the tank body 12, the purpose being 105 that the T 27 will permit gases entering through the pipe 19 to pass directly up to the top portion of the tank body 23 so as to pass to the discharge T 26 without having to bubble through the water or other liquid 110 within the tank body 23. The pipe 19 constituting the outlet from the tank 10 is, of

course connected in the intermediate branch of the T 27, and a discharge pipe 28 is connected with the corresponding intermediate branch of the T 26, this discharge pipe 28 forming or being connected with a seepage pipe which is of course buried within a suitable trench within the ground so as to distribute the matter passing from the tank.

There is an important feature, common to both tanks, namely a transversely extending vertical partition 29 which, in actual practice, may be a slab of concrete, stone or the like, having its end portion fitting with guides 30 on the inner walls of the tank and having its lower edge fitting within sockets or teeth 31 whereby this slab will be retained in position. This slab terminates at a point below the water level 32 and is provided for the purpose of preventing undue agitation of the water or other liquid in case waste matter enters the tank or tanks with considerable violence or force.

From the foregoing description and a study of the drawings, it will be apparent that I have thus provided a simply constructed, inexpensive and yet highly efficient septic tank structure which may be used in series, or individually if desired and which will act most efficiently to promote sanitation. It is believed that the construction,

operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claim.

Having thus described the invention, I claim:

A septic tank comprising a hollow body having an open top normally closed by a removable cover fitting thereon, said body being provided internally at diametrically opposite points with enlargements, an inlet pipe member embedded within one enlargement and having its discharge end directed downwardly, a T embedded within the other enlargement and constituting an outlet, the second named enlargement terminating short of the cover so as to be spaced below the same and said T having a vertically arranged branch having its upper end terminating flush with the upper end of said second named enlargement.

In testimony whereof I affix my signature.

GEORGE L. SCHIDING.
